UNITED STATES PATENT OFFICE.

FRANK W. ADSIT, OF MINNEAPOLIS, MINNESOTA.

ELECTRICAL TIMING MECHANISM.

1,196,728.

Specification of Letters Patent. Patented Aug. 29, 1916.

Application filed October 22, 1915. Serial No. 57,310.

To all whom it may concern:

Be it known that I, FRANK W. ADSIT, a citizen of the United States, residing at Minneapolis, in the county of Hennepin and State of Minnesota, have invented certain new and useful Improvements in Electrical Timing Mechanism, of which the following is a specification.

This invention relates to timing mechanism electrically wound and is adapted for use as an electrical clock, also as a part of the timing apparatus used in my co-pending application, Serial #15,114, filed March 17, 1915, and various other devices where time intervals are desired.

One object of my invention is to provide an apparatus that will be continually operative as long as electric current is supplied to it, and which will open and close an electric contact at certain predetermined intervals.

Another object of my invention is to provide means for establishing a positive contact of comparatively short duration and having the opening of the contact of comparatively long duration so that a secondary timing apparatus may be actuated through the closing of the contact without excessive use of current.

A further object of my invention is to provide means whereby the contact employed may be quickly and positively opened at the instant the opening is demanded.

With these and incidental objects in view the invention consists of certain novel features of construction and combination of parts, the essential elements of which are set forth in appended claims and a preferred form of embodiment of which is hereinafter described with reference to the drawings which accompany and form a part of this specification.

Figure 1 discloses a front elevation of the mechanism with the contact between the springs 2 and 3 closed in the normal condition when the switch 4 is opened. Fig. 2 is a front elevation of the mechanism with the contact between the springs 2 and 3 opened, the armature having been actuated by the coil 8, and Fig. 3 is an enlarged side elevation of a clip 30 and the insulation 31 mounted on the spring 3, to better illustrate the means employed to make the opening of the contact of the springs 2 and 3 positive.

With the mechanism in the condition dis-

current will flow from the battery 5 through wire 6 to the spring 3 through the contact 1 and spring 2 through wire 7, the winding of the coil 8, wire 9, through the switch 4 back to battery 5, thus energizing the coil 8 and causing it to attract its armature 9 pivoted at 10 to the frame 11, the frame and armature being constructed preferably of iron. Carried by the shoulder screw 12 the roller 13 is mounted on the armature 9 and as the armature is attracted by the coil 8 the roller 13 will ride up the cam surface 14 of the lever 15 which is pivotally mounted on the spring controlled lever 17, which in turn is pivotally mounted by the shoulder screw 18 on the frame 11, the spring 19 serving to normally hold it in the position disclosed in Fig. 1. The insulated bumper 20 travels downwardly along the spring 3 as the roller 13 riding on the cam surface 14 of the lever 15 presses that lever downwardly, the lever 17 which supports it turning angularly about the shoulder screw 18. The dog 21 pivotally mounted on the armature 9 at 22 and normally held in mesh with the ratchet wheel 23 by the spring 24 is carried forward a predetermined number of teeth by actuation of the armature 9, the retaining dog 25 mounted on the frame 11 at 26 being normally held in mesh with the ratchet wheel 23 by the spring 27. As the armature 9 is attracted by the coil 8 and moves forward the roller 13 will pass the point 28 of the lever 15 and the cam surface 29 of the lever will allow the lever 15 to turn quickly in an anti-clockwise direction, the cam surface 29 riding upwardly along roller 13, the lever 15 as a whole turning on its shoulder screw 15', on the lever 17 and the lever 17 also turning slightly on its shoulder screw 18 until the position as disclosed in Fig. 2 is reached. As soon as the point 28 has been passed by the roller 13 and the reverse motion of lever 15 starts, the bumper 20 is lifted from the spring 3 allowing the contact 1 to open and to make the opening absolutely positive and quick, the clip 30 which is screwed to the armature 9, as better shown in Fig. 3, impinges on the insulation 31 mounted on spring 3 and carries the spring 3 forward with the armature 9, the bumper 32 of felt or other suitable material mounted on the adjustable stop screw 33 serving to take up the jar of the armature 9, which is preferably of considerable weight to pro-

vide sufficient inertia to render it sluggish. The backward motion of lever 15 is regulated by an adjustable stop screw 34, and the contact 1 having been opened the armature 9 will move backward under the influence of the main spring 35, which is adjustable by the set screw 36. The dog 21 engaging the tooth of the wheel 23 at 37, Fig. 2, will tend to rotate that ratchet wheel in a clockwise direction and the motion will be retarded by a train of gears and escapement movements at 38, which are of ordinary construction and omitted for simplicity. It is evident that as soon as the armature has traveled backward overcoming the escapement retardation to the point when the roller 13 repasses the point 28 of the lever 15 that lever will quickly swing into the position disclosed in Fig. 1, thus closing the contact 1 and causing repetition of the cycle which will be repeated as long as the switch 4 is closed.

It is evident that the contact 1 may be utilized not only to break the circuit as illustrated in the drawings, but also to close circuits for secondary timers, sign flashers, or any other suitable device.

While I have described my invention and illustrated it in the drawings as one particular embodiment of the invention, it is evident that it may be applied in many ways and I do not wish myself to be understood as limiting it to the particular construction and arrangement of parts as shown in the drawings and described in the specification, but

I claim:

1. In electrical timing mechanism the combination of a coil, an armature associated with said coil, a dog mounted on said armature, an escapement movement having a ratchet wheel actuated by said dog, a roller mounted on said armature, a double cam shaped lever coacting with said roller, and means controlled by said double cam shaped lever for closing an electrical contact.

2. In electrical timing mechanism the combination of a coil, an armature associated with said coil, a dog associated with said armature, a ratchet wheel associated with said dog, means connected with said ratchet wheel for retarding its motion, a frame for mounting said armature, coil and ratchet wheel, a lever pivotally mounted on said frame, a secondary lever pivotally mounted on said first lever and having 2 camming surfaces, said camming surfaces meeting at a common point; a roller mounted on said armature and coacting with the two camming surfaces of said secondary lever.

3. In electrical timing mechanism the combination of a frame, a coil mounted on said frame, an armature mounted on said frame and adapted to be moved in one di-

rection by said coil when actuated, means for making the return motion of said armature sluggish, an electrical contact adapted to be included in the circuit with said coil and a source of electrical current, an anchor shaped lever, a roller mounted on said armature and coacting with said anchor shaped lever and an electrical contact controlled by the motion of said anchor shaped lever.

4. In electrical timing mechanism the combination of a frame, a coil mounted thereon, an armature mounted on said frame coacting with said coil, means associated with said frame and said armature for making the motion of said armature sluggish in one direction, a support lever pivoted on said frame, an anchor shaped lever pivoted on said support lever and having an arm extending therefrom, an electrical contact controlled in one direction by said arm extending from said anchor shaped lever, a roller mounted on said armature and coacting with said anchor shaped lever.

5. In electrical timing mechanism the combination of a frame, a coil mounted thereon, an armature mounted on said frame coacting with said coil, means for making the return movement of said armature sluggish, an electrical contact adapted to be included in a circuit with said coil and a source of electrical energy, a support lever pivoted on said frame, an anchor shaped lever having a right and left hand camming surface, and an arm extending from said anchor shaped lever adapted to close said contact when said anchor shaped lever is moved in one direction, and to allow the opening of said contact when said anchor shaped lever is moved in the other direction, a roller mounted on said armature and adapted to ride on both right and left hand camming surfaces of said anchor shaped lever, said contact being closed while the motion of said anchor shaped lever is on one side of said roller, and being free to open when said anchor shaped lever is on the other side of said roller, and means attached to said arm for positively opening said contact when said armature is at the forward end of its stroke under the influence of said coil.

6. In electrical timing mechanism the combination of a coil, an armature associated with said coil, two camming surfaces meeting at an apex and controlled by said armature, a normally opened contact, and means associated with said camming surfaces to close said electrical contact when raised on one of said camming surfaces, and to allow said electrical contact to open when raised on the other of said camming surfaces.

7. In electrical timing mechanism the combination of a coil, an armature associated with said coil, two camming surfaces

meeting at an apex and controlled by said armature, an electrical contact, means associated with said camming surfaces to close said electrical contact when raised on one of said camming surfaces and adapted to increase the pressure on said contact as it rides upwardly on said camming surface, and additional means on said armature for quickly opening said electrical contact when said means for closing said electrical contact pass the apex of said camming surfaces and ride on the second of said camming surfaces. 10

FRANK W. ADSIT.
